(57) **CLAIM**

The ornamental design for a beverage container, as shown and described.

DESCRIPTION

FIG. 1 is a perspective view of a beverage container showing the design.

FIG. 2 is a side elevation view of the beverage container of FIG. 1.

FIG. 3 is another side elevation view of the beverage container of FIG. 1.

FIG. 4 is another side elevation view of the beverage container of FIG. 1.

FIG. 5 is another side elevation view of the beverage container of FIG. 1.

FIG. 6 is a top plan view of the beverage container of FIG. 1.

FIG. 7 is a bottom plan view of the beverage container of FIG. 1.

FIG. 8 is a perspective view of a beverage container showing the design.

FIG. 9 is a side elevation view of the beverage container of FIG. 8.

FIG. 10 is another side elevation view of the beverage container of FIG. 8.

FIG. 11 is another side elevation view of the beverage container of FIG. 8.

FIG. 12 is another side elevation view of the beverage container of FIG. 8.

FIG. 13 is a top plan view of the beverage container of FIG. 8; and,

FIG. 14 is a bottom plan view of the beverage container of FIG. 8.

The dashed lines shown in the drawings illustrate portions of the beverage container that are not presently claimed and thus form no part of the presently claimed design. The shading lines shown in the drawings represent the approximate three-dimensional contour of the claimed design and are not intended to indicate surface decoration.
